UNITED STATES PATENT OFFICE.

BURNSIDE E. SAWYER, OF FITCHBURG, MASSACHUSETTS.

HOOK-FINISHING MACHINE.

1,187,394.

Specification of Letters Patent. Patented June 13, 1916.

Application filed July 19, 1915. Serial No. 40,585.

To all whom it may concern:

Be it known that I, BURNSIDE E. SAWYER, a citizen of the United States, residing at Fitchburg, in the county of Worcester and 5 State of Massachusetts, have invented a new and useful Hook-Finishing Machine, of which the following is a specification.

This invention relates to a finishing machine, particularly designed for forming a 10 tapered notch at the end of a crochet hook. The formation of this notch has been heretofore largely a hand operation, but by the use of my improved machine the hand operations are substantially eliminated.

15 It is the principal object of my invention to provide a hook finishing machine by which a hook and a rotating cutter may be given such relative movements that the notch formed by the cutter shall extend around 20 substantially three sides of the hook, this form of notch being essential in this product.

With this object in view, one important 25 feature of my invention relates to the provision of a cylindrical work support for holding the hook in the desired angular position during the cutting or finishing operation.

Another feature of my invention relates to the provision of suitable devices for moving 30 the work support angularly relatively to the cutter, thereby bringing different portions of the hook in position to be operated upon by the cutter.

Further features of my invention relate to 35 certain devices, arrangements, and combinations of parts which will be hereinafter described and more particularly pointed out in the appended claims.

The preferred form of my invention is 40 shown in the drawings, in which—

Figure 1 is a side elevation of the finishing machine; Fig. 2 is a front elevation thereof; Fig. 3 is an enlarged plan view of the work support and the rotating cutter, with their 45 associated parts; Fig. 4 is an enlarged end elevation of a portion of the work support taken in the direction of the arrow 4 in Fig. 3; Fig. 5 is a front elevation of the work support, portions thereof being broken away, 50 and the bearings thereof being indicated in dotted lines; Figs. 6 and 7 are plan view and side elevation of a blank suitable for forming a crochet hook, and Figs. 8 and 9 are a plan view and side elevation of the 55 same blank after the finishing operation has been performed.

The machine comprises in its essential parts a cylindrical work support 10 and a rotating cutter 11, together with suitable supporting and actuating devices by which the 60 work support and cutter may be given the necessary relative movements. The work support 10 is mounted in bearings 12 and 13 (Fig. 5) formed in a bracket or casting 14 (Fig. 1) which may be secured by bolts 15 65 to an angle plate 16.

The work support itself comprises two cylindrical bearing portions 17 and 18 (Fig. 5), the portion 17 having a pinion 19 formed thereon, which pinion is of slightly larger 70 diameter than the portion 17, thus providing a shoulder 20 which prevents axial movement of the work support toward the left, as shown in Fig. 5. The bearing portion 18 is also formed in two diameters, thus providing 75 a shoulder 21 which prevents axial movement of the work support in the opposite direction.

A segment gear 22 (Fig. 1) is pivotally mounted at 23 upon an upward extension of 80 the bracket 14 and meshes with the pinion 19 previously described. The segment gear 22 is provided with an upwardly extending handle 24 by which it may be manually operated, thereby giving the cylindrical work 85 support a partial rotation in its bearings.

A pair of stops 25 and 26 secured to the outer face of the bracket 14 engage projecting parts of the work support, thereby limiting its angular movement in both directions. 90 The stop 25 is shown in operative engagement in Fig. 1 and the stop 26 is similarly engaged in Fig. 4.

In order to yieldingly retain the work support in any angular position a block of 95 friction material 27 (Fig. 4) is secured to the upper edge of the stop 25, being held in position by a clamping plate 28 and screws 29. One end of the block 27 engages the outer end of the work support 10 with sufficient pressure to retain the work support 100 yieldingly in any desired position.

Referring now to Figs. 3, 4 and 5, the work support 10 is provided with an opening 30 extending axially through the support. As shown in Fig. 4 this opening is 105 formed as a longitudinal rectangular slot disposed radially along one diameter of the cylinder. A hook rest 31 extends axially through this slot or opening, and is provided 110 in its upper edge, with a suitable groove for receiving the hook blank. At its right hand

end, a stop 32 is provided for positioning the hook longitudinally.

The radial position of the rest 31 in the slot 30 is determined by a radially adjustable screw 33 which is threaded into a lug 34 formed upon the inner side of the bearing portion 18. At its inner end the screw 33 is provided with a ball-and-socket connection with the rest 31 and at its opposite end a screw-driver slot provides for convenient adjustment of the rest 31 toward or from the axis of the work support 10.

An outwardly extending lug or projection 35 is formed on or secured to the portion 17 of the work support 10 and the outer end of the hook rest 31 is secured by a bolt-and-slot connection to the projection 35, by which means the hook rest is rigidly retained in any desired angular position.

A clamping plate 36 extends axially through the opening or slot 30 above the rest 31, and is adapted to engage the upper side of a hook blank, positioned on the rest, thereby securing the blank within the groove in the upper face of the hook rest. The clamping device shown in the drawings comprises a short shaft or stud 37 (Fig. 3) rotatable in a middle portion 38 which connects the bearing portions of the work support. The shaft 37 is provided with a cam 39 positioned to engage the plate 36 to force the same against the hook blank. The shaft 37 is also provided with an extension 40 having a squared end 41 to which a socket wrench 42 may be applied for turning the shaft.

The parts thus far described provide means for supporting a hook blank in any desired angular relation to the axis of the work support, means for clamping the hook in the desired position, and manually operated means for giving the work support and hook a partial rotation.

I will now describe the arrangements for supporting and driving the cutter 11. The cutter is mounted upon one end of a short horizontal shaft 43 (Fig. 3) rotatable in bearings 44-44 formed in the outwardly projecting arms of a vertical cutter slide 45. The slide 45 is movable in a dove-tailed guideway 46, vertical adjustment therein being secured by turning a handle 47 mounted upon the upper end of a slide screw 48 (Fig. 2).

The guideway 46 is formed in an upwardly extending projection at the front end of a carriage 49 which is movable horizontally between guides 50 secured to a base-plate 51. The plate 51 is provided with slots 52 upon its opposite edges through which bolts 53 extend into an extension of the angle plate 16. By loosening these bolts the angular position of the carriage may be varied relatively to the axis of the work support. At its rear end

the carriage 49 is provided with a downwardly extending arm 54 (Fig. 1) having a slot-and-pin connection with an upwardly extending arm 55 forming one portion of a bell-crank pivoted to a fixed support at 56. The horizontal arm 57 of the bell-crank is connected by a rod 58 to a treadle 59 pivoted to the floor at 60.

The machine is shown herein as mounted upon the bed 61 of a work bench 62. A coiled spring 63 is connected at its upper end to the bed 61 and at its lower end to the arm 57, the spring acting to raise the arm 57, thus moving the carriage 49 to the rear. A stop-plate 64 is adjustably secured to the carriage 49 by bolts 65 and limits the forward movement of the carriage.

The cutter shaft 43 may be driven in any convenient manner and I have herein shown the shaft as provided with a pulley 66 which is connected by a belt 67 to a motor 68 mounted above the machine. This motor may be controlled by opening and closing the circuit 69 by means of a knife switch 70 operated by a depending rod or arm 71. Any other suitable control mechanism may be substituted if desired.

Having described the details of the mechanism I will now explain the operation of the machine. The hook blanks as brought to the machine have the form shown in Figs. 6 and 7, two parallel sides of the blank being slabbed off for a certain distance from one end (Fig. 6) and the two remaining sides having the corners rounded off as shown in Fig. 7. The blank thus prepared is placed upon the hook rest of the work support as shown in Figs. 4 and 5 and is secured therein by turning the shaft 37 and the cam 39 to force the clamp 36 downwardly against the upper side of the hook. The treadle 59 is then pressed downwardly, moving the carriage 49 forwardly and bringing the cutter 11 into position to cut a tapered notch into one side of the blank. While the cutter remains in its forward position the segment gear 22 is turned by means of the handle 24, revolving the work support through approximately three-fourths of a revolution, and thus presenting three sides of the blank to the action of the cutter. After the cutting operation is completed the treadle 59 is released and the spring 63 returns the carriage 49 to its rearward position. At the same time the handle 24 is swung upwardly, turning the work support 10 to its normal position. The form of the hook after the cutting or finishing operation is completed is shown in plan and elevation in Figs. 8 and 9.

It will be noted that the work support 10 revolves in fixed bearings, whereas both the vertical and horizontal position of the cutter shaft 43 as well as its angular relation to the work support 10 may be adjusted as desired.

Furthermore, the angular relation of the hook rest 31 with reference to the work support may be varied by means of the adjusting screw 33 and the bolt-and-slot connection 5 to the projection 35. The several adjustments described provide for variations in the depth and inclination of the notch for different sizes and styles of hooks.

Having thus described my invention it 10 will be evident that changes and modifications can be made therein by those skilled in the art without departing from the spirit and scope thereof as set forth in the claims, and that the invention can be used for finishing other articles than the one mentioned, and I do not wish to be otherwise limited to the details herein disclosed, but

What I do claim is:—

1. A finishing machine having, in combination, a cylindrical work support, a work rest extending longitudinally through an axial opening in said support, means for securing said rest in adjusted angular position in said support, means for clamping the 25 work in position on said rest, a rotary cutter, a stand therefor, guideways for said stand, means for advancing said cutter and stand along said guideways to operative position adjacent to said work, and manually 30 operated means for partially rotating said cylindrical support while said cutter is in operative position.

2. A hook finishing machine having, in combination, a cylindrical work support, a hook rest extending through an axial opening in said support, means for securing said rest in adjusted angular position in said support, means for clamping the hook in position on said rest, a rotary cutter, means for 35 advancing said cutter to operative position adjacent to said hook, manually operated means for partially rotating said cylindrical support while said cutter is in operative position, and a pair of oppositely disposed 40 stops effective to limit the angular movement of the work support in both directions.

3. A hook finishing machine having in combination a cylindrical work support, a hook rest extending through an axial opening in said support, means for securing said rest in adjusted angular position in said support, means for clamping the hook in position on said rest, a rotary cutter, means for advancing said cutter to operative position 45 adjacent to said hook, manually operated means for partially rotating said cylindrical support while said cutter is in operative position, and a pair of oppositely disposed stops effective to limit the angular movement

of the work support in both directions, one 60 of said stops having a friction device mounted thereon and engaging the outer end of the work support to yieldingly retard the angular movement thereof.

4. In a hook finishing machine a cylindrical work support having an axial opening therethrough, a hook rest extending through said support, a screw adjustable radially in said support and having a ball-and-socket connection with said hook rest, said cylindrical support having an axial extension at one end, and said hook rest having a bolt-and-slot connection with said extension whereby said rest may be secured in any desired angular position relatively to the axis 75 of the support.

5. A hook finishing machine having, in combination, a support for a hook blank rotatable in fixed bearings, manually operated means to partially rotate said support, a rotary cutter and shaft, bearings for said shaft, adjustable vertically and angularly relatively to said support, means to secure said bearings in adjusted position, means to advance said cutter in a predetermined horizontal path to operative position, and means to rotate said cutter.

6. A hook finishing machine having in combination a rotatable work support, means to position and secure a hook blank in said support at any desired angle to the axis thereof, manually operated means effective to give said support a partial rotation, a rotary cutter, a stand for said cutter, guideways along which said stand is movable in a predetermined straight path, means to withdraw said cutter and stand normally to a position removed from said hook blank, means to advance said cutter and stand along said guide-ways toward the blank, and an adjustable stop to limit the latter movement.

7. A hook finishing machine having, in combination, a rotatable work support, means to position and secure a hook blank in said support at any desired angle to the axis thereof, manually operated means effective to give said support a partial rotation, a rotary cutter and a shaft, bearings for said shaft formed on a vertical slide, means to move said slide vertically, a carriage supporting said slide, manually operated means to move said carriage forward, and additional means to return said carriage to rearward position, said carriage being also adjustable angularly in a horizontal plane.

In testimony whereof I have hereunto set my hand.

BURNSIDE E. SAWYER.
